(57) **CLAIM**

The ornamental design for a hemostasis device, as shown and described.

DESCRIPTION

FIG. 1 is an isometric top view of a hemostasis device.

FIG. 2 is an isometric bottom view thereof.

FIG. 3 is a top plan view thereof.

FIG. 4 is a front elevational view thereof.

FIG. 5 is a bottom plan view thereof.

FIG. 6 is a rear elevational view thereof.

FIG. 7 is a left side elevational view thereof.

FIG. 8 is a right side elevational view thereof.

FIG. 9 is a perspective view of the hemostasis device in use; and,

FIG. 10 is a perspective view of the hemostasis device in use.

The broken lines showing a hand in FIGS. 9-10 depict environmental subject matter that forms no part of the claimed design. All other broken lines depict portions of the hemostasis device that form no part of the claimed design.
